UNITED STATES PATENT OFFICE

GEORGE H. DAUBNER, OF PONTIAC, MICHIGAN, ASSIGNOR TO YELLOW TRUCK & COACH MANUFACTURING COMPANY, OF PONTIAC, MICHIGAN, A CORPORATION OF MAINE

ENGINE SUPPORT

Application filed February 1, 1928. Serial No. 251,186.

This invention relates to motor vehicles and more particularly to engine mountings and the like.

While not limited in its use, the invention is particularly adapted for use with taxicabs and other commercial automobiles, trucks and busses which are run exceptionally hard and by drivers who are at times inclined to be somewhat careless and frequently figure in collisions in the heavy traffic in which they are called upon to operate.

In the past, the general practice has been to rigidly mount an engine in the chassis frame, and the experience has been that a severe impact tending to cause frame distortion, particularly that which involves relative longitudinal movement with the side rails, imposes such terrific strains on the engine and its mounting as to cause damage and breakage, necessitating costly repairs as well as tying up the use of the vehicle during the time repairs are being made. The part that usually breaks is the bell housing or casing for the flywheel and clutch, of which the engine supporting legs are an integral part, and the repair of the damage necessitates complete removal of the engine from the chassis, and the substitution of a new housing, which at times may mean a delay of several weeks before a new housing can be secured from a source of supply which may be situated at a distantly located point.

It is one of the objects of the present invention to provide an improved arrangement for mounting an engine which normally will firmly hold the engine in a definite location in the chassis frame but which, in the event of frame distortion, such as has heretofore caused breakage of the bell housing, will permit a relative movement of the engine in the mounting to compensate for the distortion whereby the engine is relieved of the damaging strains.

A preferred, but not necessarily the only embodiment of the invention, is illustrated in the accompanying drawing wherein Fig. 1 is a transverse sectional view of a chassis frame with an engine mounting therein in accordance with the invention.

Fig. 2 is a view looking in the direction of the arrows on line 2—2 of Fig. 1.

Fig. 3 is a section on line 3—3 of Fig. 1, and Fig. 4 is a plan view of one of the engine supporting brackets.

Referring to the drawing, the numerals 1—1 indicate a pair of channel shaped, longitudinally extending side sills or members of a chassis frame, in which is to be supported the engine 2 shown in outline. At the rear of the engine, the bell housing or casing is provided with a pair of integral laterally extending arms or legs 3—3, each of which is provided with a head 4 having a peripheral groove for the reception of a body or pad 5 of insulating or cushioning material, such as rubber or other similar elastic composition, held in place by a pair of encircling, separable retainer members 6—7 detachably secured to each other by bolts 8. The lowermost retainer member 7 rests upon a supporting bracket carried by the longitudinal frame member 1. This bracket consists of a pair of plate-like members 9 and 10, the member 10 being secured by bolts or rivets 11 to the lower flange of the channeled frame member 1 and the member 9 being secured by rivets or bolts 12 to the vertical web of the frame member, the two plates each having overlapping end portions preferably welded or otherwise united with each other and provided with aligned openings through which a long fastening pin 80 or bolt 13 extends upwardly into threaded engagement with the lower retainer member 7. Between the head of the bolt 13 and the underside of the bracket are a pair of oppositely disposed cups 14—14 forming seats for helically coiled spring 15 which serves to yieldingly maintain the engine arm on the bracket. Bracing strap 16 is secured at one end by bolt 17 to the upper retainer member 6 and at its opposite end by bolt 18 to an angle iron member 19, welded, riveted, or otherwise fastened to the upper end of the bracket plate 9.

One of the mounting brackets differs from the other, in that the opening for the long bolt 13 in one instance is circular and of substantially the same diameter as the bolt, while in the other the opening comprises an elongated slot in which the bolt may slide in the event of frame distortion, such slotted bracket being located at the right in Fig. 1.

Referring particularly to Figs. 3 and 4, showing the parts in greater detail, the reference character 20 indicates the elongated slot in the bracket members 9 and 10. In order to position the engine arm in definite relation on the bracket, there is provided a thin sheet metal plate 21 over the slot and between the bracket and retainer member 7, secured to the bracket by one or more bolts 22, and having a circular opening through which the fastening bolt 13 passes. The engagement of the sheet metal plate with the bolt 13 serves to locate the parts in fixed position. However, in the event of a collision, when the impact or shock are such as to cause the frame members to move relative to each other, the sheet metal plate will be torn or split to permit the dependent bolt to slide in the slot, thus compensating for frame distortion and relieving the bell housing and associated parts from damaging strains.

The destruction of the plate is, of course, a matter of small importance and obviously of less seriousness than breakage of the bell housing, since the replacement of a new plate may be readily made at little or no cost and in a comparatively short time. Furthermore, the destruction of the plate does not disable the vehicle as would a broken bell housing, for even though the locating plate may be destroyed, the engine arm will still be supported on the bracket and held thereon by the bolt 13 so that the vehicle may be run without any harmful effects on the driving connections, until a convenient opportunity presents itself for the replacement of a damaged plate by a new plate. To make the replacement it is not necessary to remove the engine from the chassis frame but the mere detachment of the two bolts 13 and 17 will permit the side of the engine to be jacked up or lifted off the supporting bracket a slight distance sufficient to allow the damaged plate to be slid from between the part 7 and bracket plate 9 after removal of the fastening bolt 22 and a new plate can then be inserted. After the new plate is secured by the bolt 22, the engine arm is dropped back on the supporting bracket and fastened by the bolts 13 and 17. Repair of the damage is thus a matter of a few minutes time and trifling cost. A supply of plates can be kept on hand or they may be readily made up on short notice from scraps at any community tin shop, garage or similar place having facilities for cutting and punching holes in sheet metal.

As an alternative construction, the plate may be made of heavier stock and the bolt 22 weakened so as to be sheared in two upon strain, which will permit the bolt 13 to slide in the slot as before described.

The bracing strap 16 associated with the slotted bracket is provided with a slotted opening 23 on which the bolt 17 may slide

when the engine arm is moved on the bracket, the bracing plate being swung about the bolt 18 as indicated by the dotted lines in Fig. 2.

I claim:

1. In combination, an engine, a supporting member therefor, arranged to permit relative movement of the engine therewith, and means associated with one of said members to normally maintain the parts in definite relation with each other, but adapted for destruction to relieve said members of strains.

2. In combination, a supporting bracket having an elongated slot therein, an engine having an arm resting on said bracket with a dependent stud projecting into said slot, and a sheet metal plate interposed between said engine arm and bracket and secured to said bracket over said slot and having an opening through which said dependent stud projects to locate the engine arm in definite relation on said bracket.

3. The structure as claimed in claim 2 together with means to yieldingly maintain the engine arm on said bracket.

4. An engine mounting, including an engine arm, resilient cushioning material associated with said arm, retainer elements for said cushioning material, a supporting bracket having an elongated slot therein, a stud extending through said slot into engagement with one of said retainers, spring means associated with the stud to yieldingly maintain the engine arm on said bracket, and a comparatively thin and readily destructible plate carried by the bracket over said slot and engageable with said stud to normally locate and hold the stud against movement in said slot, but destructible upon strain to permit said movement.

5. In a motor vehicle, the combination with a chassis frame and an engine to be supported thereon, having lateral arms at each side thereof, of means to mount one of said arms on the frame, and means to mount the other of said arms to permit relative longitudinal movement with said frame upon frame distortion, said last mentioned means including a bracket having an elongated slot, through which a dependent stud on the engine arm extends, and a readily destructible plate located over said slot and engageable with said stud to normally hold the engine in definite relation on said bracket, but destructible upon the imposition of undue strain to allow the stud to move in said slot.

6. In a motor vehicle or the like, a chassis frame, an engine to be mounted therein, a plurality of supporting connections between the engine and frame, one of which is a loose connection to permit relative movement of the engine and frame and means associated with the loose connection, destructible upon strain to allow relative movement of the en-

gine and frame but normally holding said connection against looseness.

7. In a motor vehicle or the like, a supporting frame, a body having a part resting on the frame, a loose connection between the frame and body part to permit relative longitudinal movement thereof upon strain, and means normally holding the parts rigid to resist relative longitudinal movement between the parts, but being fracturable upon abnormal strain to permit such movement.

8. In a motor vehicle or the like, a supporting frame, a body to be supported having a loose connection with the frame, and a destructible locating element for the parts which is breakable upon strain to allow relative movement of the parts thru the loose connection.

9. In a motor vehicle or the like, a supporting frame, an engine to be supported in the frame having a lateral pin extending thru an elongated slot in the frame, and a locating element to normally hold the pin against sliding movement in the slot but breakable upon strain to permit such movement.

10. In a construction of the character described, two parts to be connected, a projection on one part extending loosely thru an elongated slot in the other part for movement therein, and a destructible locating element interposed between the parts and removably secured to the slotted part, having an aperture thru which the projection extends in close fitting relation.

11. In a construction of the character described, two parts to be connected, a projection on one part extending loosely thru an elongated slot in the other part for movement therein, a locating element interposed between the parts and having an aperture thru which the projection extends in close fitting relation and a fastening element for securing the first element to the slotted part, one of said elements being destructible to allow movement of the projection in the slot.

12. In a construction of the character described, a load carrying member, a member to be mounted thereon, means to loosely attach the one member on the other, and a frail locating element normally resisting relative movement of the members in a horizontal direction and being fracturable upon abnormal strain to allow such movement.

13. In a construction of the character described, a projection on one part extending loosely through an elongated slot in the other part for sliding movement therein in the direction of elongation, and destructible locating means to normally hold the projection in definite position in the slot and which is breakable upon abnormal strain to permit the projection to slide in the slot.

In testimony whereof I affix my signature.
